UNITED STATES PATENT OFFICE.

EUSTACE MORIARTY WESTON, OF BRAK PAN, TRANSVAAL.

WATER-SUPPLYING DEVICE FOR ROCK-DRILLING MACHINES.

No. 899,582.

Specification of Letters Patent. Patented Sept. 29, 1908.

Application filed February 18, 1908. Serial No. 416,596.

To all whom it may concern:

Be it known that I, EUSTACE MORIARTY WESTON, a subject of the King of Great Britain, and resident of Brakpan, Transvaal, have invented certain new and useful Improvements in Water-Supplying Devices for Rock-Drilling Machines, of which the following is a specification.

This invention relates to water supplying devices or attachments for rock-drills or rock-drilling machines.

In the specifications of certain prior patents granted to me under No. 842598 dated 29th January, 1907, and No. 849445 dated 9th April, 1907, I describe an attachment or device for supplying water through the drill steel or bit of a rock-drilling machine to the hole being drilled, which consists of a sleeve non-rotatably mounted round the drill steel or bit and a loose water supply ring or swivel mounted round said sleeve. This construction, necessary when the drill steel or bit is rotated in one direction only, is not necessary when an oscillatory motion is imparted to the drill steel or bit to change the position of its cutting edge or edges in relation to the rock.

The object of my present invention is to provide a device or attachment especially applicable for those types of drills or machines in which such oscillatory motion is imparted to the drill or bit.

The invention is equally applicable to hammer or piston drills in which an oscillatory motion is imparted to the drill steel or bit.

The invention will now be fully described by aid of the accompanying drawings in which

Figure 1 is a part sectional elevation of the shank end of a drill steel or bit with the water supplying attachment in operative position thereon. Fig. 2 is a transverse section of the drill steel. Fig. 3 is a transverse section of Fig. 1 on the line $x-x$, and Fig. 4 is a view similar to Fig. 3 but illustrating a slight modification of the invention.

1 represents the drill steel or bit with a hole 2 extending through it, preferably from end to end. A portion 3 of the shank of the steel or bit 1 is made taper in a rearward direction. This tapered portion 3 of the shank may, as shown in Figs. 1 and 3, be of circular cross-section. In the tapered portion 3 is formed one or a plurality of transverse and

forwardly inclined holes or passages 4 communicating at their inner ends with the longitudinal and axial hole 2 and at their outer ends terminating in the surface of the tapered portion 3.

Around the tapered portion 3 of the shank (or it may be any suitable portion thereof) is arranged a sleeve 5 which internally is bored out or made to fit the tapered portion 3 of the steel or bit 1, that is to say if the tapered portion 3 of the steel is, as shown in Fig. 3, of circular transverse section, then the bore of or hole in the sleeve 5 is of corresponding circular cross-section.

Inside the sleeve 5 and surrounding the tapered portion 3 is an annular recess 7 with which the outer end (or ends) of the transverse forwardly inclined hole 4 (or holes) communicates.

The sleeve 5 is constructed with a tail piece or projection 8 (through which is formed a passage 9 communicating with the recess 7) for attaching thereto, by means of an ordinary hose clamp 10, or in any other suitable manner, a hose or other suitable flexible pipe 11, which serves for conducting water or other suitable liquid to the annular recess 7 in the sleeve 5.

The hose or flexible pipe 11 communicates with any convenient source of water or liquid supply, which may be under pressure so as to force it through the pipe 11 and passage 9 and recess 7 in the sleeve 5, and from the latter through the transverse hole 4 and longitudinal hole 2 in the drill steel or bit to the cutting end thereof.

Instead of placing the water under pressure, it may be drawn by creating or tending to create a vacuum in the water supply passages, as for example by permitting a quantity of the compressed air or operating fluid to pass from the machine along the drill steel, for which latter purpose the longitudinal hole 2 may, as shown in Fig. 1, be extended beyond the transverse hole 4 in a rearward direction, so as to communicate with the cylinder of the machine; or such compressed air supply may be provided in any other convenient manner and either the live or exhaust air be utilized for the purpose.

The sleeve 5 as shown is fashioned in one piece with (it may be a separate part attached to the sleeve in any convenient manner) a handle or projection 12, (or handles or

projections), for imparting by hand the oscillatory motion to the drill steel or bit 1, through the medium of said sleeve 5.

In Fig. 4 I show a modification in which 5 the tapered portion 13 of the drill steel or bit is made of hexagonal cross-section. In this case the bore or tapered hole in the sleeve 16 is made of corresponding hexagonal transverse section. It will be apparent that said 10 tapered portion 13 and bore of the sleeve 16 may be made of any other suitable polygonal cross-section.

An advantage of the above described constructions is that the drill steel or bit can be 15 oscillated independently of the machine. When oscillated independently of the machine that portion 2^a of the bit shank which enters the machine may be rounded as shown in Fig. 1, or when the steel or bit is oscillated 20 through the medium of the front head bushing or other part of the machine, said portion 2^a of the shank may be made of any desired polygonal transverse section, corresponding to the hole in which it fits.

25 What I claim as my invention and desire to protect by Letters Patent is:—

1. In a device such as described, in combination, a drill steel or bit the shank of which has a tapered portion and provided with a 30 longitudinal hole and a transverse hole communicating with said longitudinal hole and communicating with the surface of said tapered portion, and a sleeve having a tapered bore corresponding to the tapered portion 35 of the steel or bit shank, the said tapered portion of the shank fitting in the said tapered bore of the sleeve, said shank and sleeve forming a recess between them in communication with the transverse hole, 40 and means non-rotatably attached to the sleeve for conveying water to said recess.

2. In a device such as described, in combination, a drill steel or bit, the shank of which has a tapered portion and provided with a 45 longitudinal hole and a transverse hole communicating with said longitudinal hole and terminating at the surface of said tapered portion, and a sleeve having a tapered bore corresponding to the tapered portion of the 50 steel or bit shank, said tapered portion of the shank fitting in said tapered bore of the sleeve and a portion of said sleeve bore being enlarged to form a water space surrounding the tapered portion of the bit shank and in 55 communication with the transverse hole, and means movable with the sleeve for conveying water to said water space.

3. In a device such as described, in combination, a drill steel or bit, the shank of which 60 has a tapered portion and provided with a longitudinal hole and a transverse hole communicating with said longitudinal hole and terminating at the surface of said tapered portion, and a sleeve having a tapered bore corresponding to the tapered portion of the 65 steel or bit shank, said projection having a hole in communica-

steel or bit shank, said tapered portion of the shank fitting in said tapered bore of the sleeve and a portion of said sleeve bore being enlarged to form a water space surrounding the tapered portion of the bit shank and in 70 communication with the transverse hole, and means for conducting water to the water space comprising a projection formed on the sleeve, said projection having a hole in communication with the water space, a flexible 75 pipe in communication with said hole and means for securing said flexible pipe to said projection.

4. In a device such as described, in combination, a drill steel or bit the shank of which 80 has a tapered portion and provided with a longitudinal hole and a transverse hole communicating with said longitudinal hole and communicating with the surface of said tapered portion, and a sleeve having a tapered 85 bore corresponding to the tapered portion of the steel or bit shank, the said tapered portion of the shank fitting in the said tapered bore of the sleeve, said shank and sleeve having a recess between them in communication 90 with the transverse hole, means non-rotatably attached to the sleeve for conveying water to said recess, and means whereby the sleeve may be rocked to oscillate the drill 95 steel or bit, as set forth.

5. In a device such as described, in combination, a drill steel or bit, the shank of which has a tapered portion and provided with a longitudinal hole and a transverse hole communicating with said longitudinal hole and terminating at the surface of said tapered portion, and a sleeve having a tapered bore corresponding to the tapered portion of the steel or bit shank, said tapered portion of the shank fitting in said tapered bore of the sleeve 100 and a portion of said sleeve bore being enlarged to form a water space surrounding the tapered portion of the bit shank and in communication with the transverse hole, means movable with the sleeve for conveying water 105 to said water space, and means whereby the sleeve may be rocked to oscillate the drill steel or bit, as set forth.

6. In a device such as described, in combination, a drill steel or bit the shank of which 110 has a tapered portion and provided with a longitudinal hole and a transverse hole communicating with said longitudinal hole and terminating at the surface of said tapered portion, and a sleeve having a tapered bore 115 corresponding to the tapered portion of the steel or bit shank, said tapered portion of the shank fitting in said tapered bore of the sleeve and a portion of said sleeve bore being enlarged to form a water space surrounding the 120 tapered portion of the bit shank and in communication with the transverse hole, means for conducting water to the water space comprising a projection formed on the sleeve, said projection having a hole in communica- 125

tion with the water space, a flexible pipe in communication with said hole, means for securing said flexible pipe to said projection, and means whereby the sleeve may be rocked 5 to oscillate the drill steel or bit, as set forth.

7. In a device such as described, in combination, a drill steel or bit the shank of which has a tapered portion and provided with a longitudinal hole and a transverse hole communicating with said longitudinal hole and terminating at the surface of said tapered portion, and a sleeve having a tapered bore corresponding to the tapered portion of the steel or bit shank, said tapered portion of the 10 shank fitting in said tapered bore of the sleeve, the said tapered portion of the shank and sleeve having an annular space between them in communication with the transverse hole, means rigid with the sleeve for conveying 15 water to said space, and means rigid upon the sleeve whereby it may be rocked to impart oscillatory motion to the steel or bit.

8. In a device such as described, in combination, a drill steel or bit the shank of which 20 has a tapered portion and provided with a longitudinal hole and a transverse forwardly

inclined hole communicating with said longitudinal hole and terminating in the surface of said tapered portion, and a sleeve having a tapered bore corresponding to the tapered portion of the steel or bit shank, said tapered portion of the shank fitting in said tapered bore of the sleeve and a portion of said sleeve being enlarged to form a water space surrounding the tapered portion of the bit shank 30 and in communication with the transverse forwardly inclined hole, means for conveying water to said water space comprising a projection formed on the sleeve, said projection having a hole leading to the water space, a 35 flexible pipe in communication with said latter hole, means for securing said flexible pipe to said projection, and means comprising a projection rigid upon said sleeve whereby it may be rocked to oscillate the drill steel or bit. 40 45

In witness whereof I have hereunto set my hand in the presence of two subscribing witnesses.

EUSTACE MORIARTY WESTON.
